(57) **CLAIM**

The ornamental design for a cap for bottle, as shown and described.

DESCRIPTION

The patent or application file contains at least one drawing executed in color. Copies of this patent or patent application publication with color drawing(s) will be provided by the Office upon request and payment of the necessary fee.

1. Cap for bottle

1.1 is a perspective view.

1.2 is a front view.

1.3 is a back view.

1.4 is a left view.

1.5 is a right view.

1.6 is a top view.

1.7 is a bottom view.

1.8 is a bottom perspective view.

1.9 is a cross-sectional view.

1.10 is a perspective view shown in a state of use.

The hand shown in blue in reproduction 1.10 forms no part of the claim.
